FREDERIC MAHOUDEAU, OF NEW YORK, N. Y., ASSIGNOR TO THE AMERICAN SUGAR REFINING COMPANY, OF NEW YORK, N. Y., A CORPORATION OF NEW JERSEY.

METHOD OF DRYING SUGAR.

SPECIFICATION forming part of Letters Patent No. 686,677, dated November 12, 1901.

Application filed January 4, 1901. Serial No. 42,141. (No specimens.)

To all whom it may concern:

Be it known that I, FREDERIC MAHOUDEAU, a citizen of the Republic of France, residing at New York city, county and State of New York, 5 have invented a Method of Drying Sugar, of which the following is a specification.

My invention relates to a method of drying sugars, although it may be used for drying other bodies, and to apparatus for carrying 10 said method into effect.

The apparatus and method of operation heretofore made use of for drying sugar and similar bodies involved the introduction of such bodies into the lower portion of a furnace-chamber having its source of heat at the bottom, and hence into the hottest portion of such chamber; then after moving the body through the hottest portion of the chamber moving it upward at the rear of the chamber 15 and causing it to traverse a path of lower temperature at the top of the furnace-chamber, and so out of the chamber. This practice has been found objectionable owing to the fact that the slowly-moving highly-heated 20 currents of air at the bottom of the furnace-chamber do not readily separate the moisture from the bodies to be dried and that such moisture as is separated in rising deposits upon or is reabsorbed by the bodies traversing the top of the furnace-chamber and moving 25 toward the outlet of the furnace-chamber. To overcome the objections stated, I have devised a construction and method of operation which involves the introduction of the bodies 30 to be dried into the upper portion of the furnace-chamber and to traverse vertical zones of gradually-increasing temperature and then descend to the lower portion of the furnace-chamber and traverse zones of gradually-decreasing temperature. The furnace-chamber 35 is arranged to have created within it at its upper part rapidly-moving air-currents of moderate but gradually-increasing temperature from without inward, which practice has 40 shown to be the best means of quickly removing the moisture, and at the bottom slowly-moving air-currents of high but gradually-decreasing temperature, which serve to 45 effect the final drying of the bodies passing 50 through the furnace.

The object of my invention is to rapidly and effectually eliminate the moisture from sugar or other bodies.

The accompanying drawings will serve to illustrate my invention.

Figure 1 is a longitudinal section and elevation of the furnace-chamber. This view also shows an exhaust-blower in elevation. Fig. 2 is an end view taken on the line X X of Fig. 1 looking from the right.

In the drawings, A represents the furnace-chamber, which I prefer to construct as a long narrow chamber rectangular in section. The top of the chamber, however, may be arched or given any other suitable shape. 65 Arranged within the chamber on suitable bracket-supports B are the horizontal trackways C C'. These trackways occupy horizontal planes throughout the greater portion of their length, and at the rear end of the furnace have their ends arranged concentrically for a portion of their length. The rear end of the trackway C is turned downward at C² and the rear end of the trackway C' turned upward, as at C³, a space being left between 70 the trackways. Mounted at opposite ends of the chamber are the shafts D, carrying at each end the sprocket-wheels E E', over which is arranged the endless link chain F. The link chain F is provided upon its outer surface with the projections G. The sprocket-wheels E' at the rear of the furnace carry on the outer side of their periphery projecting hook portions H. It will be observed from 75 the drawings that the link chain F has a movement parallel with the trackways C C' and that in the rotation of the sprocket-wheels E' the projecting hook portions H are carried when in the highest position slightly above the top of the link chain.

I represents baskets by which the material to be dried is carried through the furnace-chamber. The baskets consist of a body portion J, preferably formed of perforated metal or wire-netting J'. Projecting upward from 90 the basket are arms K, carrying horizontal bearings L, on which wheels M are loosely mounted.

N N' represent openings in the front of the furnace-chamber, through which the material 95

- is introduced into the furnace-chamber and withdrawn therefrom, and O a source of heat in the bottom of the furnace-chamber. This source of heat I prefer to consist of a steam-
5 coil arranged as shown—that is, nearer to the front end of the furnace-chamber than to the rear end—although I may extend the steam-coil nearer to the rear end of the chamber than is shown in the drawings.
- 10 P represents an exhaust-blower having its draft-pipe Q connected to the interior of the furnace-chamber at the top and rear end. By this arrangement of heat and draft apparatus I am enabled to obtain a circulation of
15 air substantially in the direction indicated by the arrows R and to produce within the furnace along its upper part rapidly-moving air-currents of gradually-increasing temperature and along the bottom part slowly-mov-
20 ing air-currents of gradually-decreasing tem-
perature.
- In operating the furnace the baskets containing the material to be dried are introduced through the opening N, with the wheels
25 M upon the trackway C. The carriage is pushed forward until the projections G upon the links F impinge upon the bearings L, on which the wheels M are mounted, thus mov-
ing the carriages forward along the trackway
30 C until the wheels E' are reached. At this point the hook projections H move under the bearings L and support the carriage and bas-
ket as they are shifted downward to the track-
way C'. Here the projections G on the link
35 chain again impinge upon the bearings L

from behind and carry the carriages and bas-
kets along the trackway C' until the opening
N' of the furnace-chamber is reached. At
this point the carriage and basket may be re-
moved from the trackway C' or diverted along 40
an outside trackway. (Not shown.)

Having thus described my invention, I
claim—

1. The herein-described method of drying
sugar, which consists in subjecting said body 45
first to the action of moving air-currents of
gradually-increasing temperature, then to the
action of moving air-currents of decreasing
temperature.

2. The herein-described method of drying 50
sugar, which consists in subjecting said body
first to the action of moving air-currents of
gradually-increasing temperature, then to the
action of moving air-currents of decreasing
temperature but of relatively higher tempera- 55
ture than the first-named air-currents.

3. The herein-described method of drying
sugar, which consists in transporting said
body first through zones of gradually-increas- 60
ing temperature, then through zones of grad-
ually-decreasing temperature, and while pass-
ing through said zones to the action of mov-
ing heated air-currents.

In testimony whereof I affix my signature
in the presence of two witnesses.

FREDERIC MAHOUDEAU.
